US00D934859S

(12) **United States Design Patent** (10) **Patent No.:** **US D934,859 S**
(45) **Date of Patent:** **** Nov. 2, 2021**

(54) **CAR SHARE ELECTRONIC
COMMUNICATION DEVICE**

(71) Applicant: **Geotab Inc.**, Oakville (CA)

(72) Inventors: **Marc James Christelis**, Mississauga (CA); **Sajjad Karimi**, Mississauga (CA); **David Bassem G E Saweris**, Mississauga (CA)

(73) Assignee: **Geotab Inc.**, Oakville (CA)

(**) Term: **15 Years**

(21) Appl. No.: **29/714,928**

(22) Filed: **Nov. 26, 2019**

(51) LOC (13) Cl. **14-02**

(52) U.S. Cl.

CLAIM

The ornamental design for a car share electronic communication device, as shown and described.

DESCRIPTION

FIG. 1 is a top, front, right side perspective view of a car share electronic communication device;

FIG. 2 is a bottom, front, left side perspective view thereof;

FIG. 3 is a bottom, rear, right side perspective view thereof;

FIG. 4 is a top, rear, left side perspective view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a rear elevation view thereof; and,

FIG. 10 is a front elevation view thereof.

The dash-dash broken lines show portions of the car share electronic communication device that form no part of the claimed design.

1 Claim, 4 Drawing Sheets
